BORE SIGHTING FIXTURE

Paul F. Peterson, Los Angeles, Calif., assignor to
North American Aviation, Inc.

Application April 22, 1946, Serial No. 663,802

2 Claims. (Cl. 33—46)

1

This invention relates to the bore sighting of guns mounted in aircraft or the like. In general, its object is to provide a fixture by which the barrels of machine guns or the like may be properly oriented after initial orientation without the necessity of leveling the plane or using a target located remotely as in conventional sighting procedure.

A specific object of the invention is to provide an apparatus embodying a miniature target adapted to be fixed directly to an airplane in line with the barrel of a gun previously aligned, so that further sighting of the gun barrel may be accomplished irrespective of the position or location of the plane.

Another object of the invention is to provide a fixture such as that referred to in the preceding paragraph, embodying means for adjusting the target with reference to the airplane. A still further object is to provide a target having means for accurately gauging a desired amount of adjustment thereof. A still further object is to provide such a target, having means for gauging adjustment thereof both in elevation and in azimuth.

Other objects will become apparent in the ensuing specifications and appended drawings in which:

Fig. 1 is a front elevation of a target device embodying my invention;

Fig. 2 is a plan view of the same from the under side thereof, parts being broken away and shown in section in order to illustrate the construction thereof;

Fig. 3 is a vertical transverse sectional view through a portion of an aircraft wing with a machine gun and my improved bore sighting apparatus attached thereto;

Fig. 4 is a plan view of a portion of the aircraft wing with a portion of a machine gun and by improved apparatus attached thereto.

As an example of one form in which the invention may be embodied, I have shown in the drawings a bore sighting apparatus particularly adaptable for bore sighting a machine gun 5 that is mounted in the wing 6 of an airplane, with the muzzle of its barrel 7 spaced from the leading edge 8 of the wing. The machine gun is mounted on a universal pivot 9 intermediate its ends, and near its rear end is provided with mechanism 10 by means of which it may be adjusted either horizontally or vertically.

Initially, the gun 5 is bore sighted by a conventional target method. That is, the plane is

leveled in front of a target which is located at a pre-determined distance therefrom, the target is then sighted through the bore of the gun, and the gun is adjusted until the line of sight intersects a pre-determined point on the target in accordance with the firing pattern that is to be established. This operation is repeated for each of the guns of the airplane. The gun mounts are locked with the guns in the positions thus determined.

The aircraft is fitted with a blast tube 11 for each gun, and a pair of fittings 12 cooperate with the target device 15 in any subsequent bore sighting operations. Each blast tube 11 comprises a sleeve into which the muzzle of the gun barrel projects. On either side of the forward ends of the blast tubes fittings 12 are secured to the inner surface of the skin of the wing 6 at the leading edge 8. After the guns have been bore sighted as aforesaid, the pairs of fittings 12 are each jig drilled with a pilot hole 13 adapted to receive the pilot pins 14 of the target device 15.

The target device 15 comprises a frame 16 having at its ends, bosses 17 in which are mounted the pins 14, and having a central opening 18. Over the opening 18 is secured a transparent target window 19 having imprinted thereon a target 20 and cross-hair lines including vertical lines 21 and horizontal lines 23. The lines 21 and 23 are arranged at 90 degrees to each other and, extended, would intersect the center of the target 20.

The forward face of the frame 16 serves as a dial face and is imprinted with vertical scales 24 and horizontal scales 25.

The target window 19 is connected to the frame 16 by studs 26 which extend through longitudinal slots 27 in the window 19 and through vertical slots 28 in the frame 16. Knurled thumb nuts 29 are threaded onto the ends of the studs 26 and engage spring washers 30 which in turn engage the surface of the target window 19. Heads 31 on the other ends of the studs 26 engage the rear side of the frame 16.

By loosening the thumb nuts 29, it becomes possible to slide the target window 19 either vertically or horizontally. A pre-determined vertical setting may be quickly effected by registering the cross-hairs 23 with selected marks on the scales 24, and in a like manner a pre-determined horizontal setting may be effected by registering the vertical cross-hairs 21 with pre-selected marks on the vertical scales 25. The 55 readings on the scales 24 and 25 may be deter-

mined by reference to previously prepared charts. For each of a series of desirable fire patterns, there may be a chart giving the readings from which that fire pattern can be realized by bore sighting the guns of the airplane to the readings given for the respective guns.

The original target bore sighting of the guns forms the basis for locating the fixture 15 by means of the fittings 12. Thus, a jig having a target identical with 20 is applied to the leading edge of the wing and sighted to determine the position in which the holes 13 shall be drilled, and the position of the target device for this purpose is determined by sighting through a barrel 7 and lining up the target 20 therewith. Previous to this sighting, the target window 19 is properly set with reference to the dial scales 24 and 25 to correspond to the scale readings for the particular pattern of the original bore sighting. This pattern is preferably a normal or neutral one in which the cross hairs 23 and 21 are lined up with central readings on the scales 24 and 25, such as "50 elevation" and "10 azimuth". In this case, the setting 50 would represent the elevation of the guns above the horizontal in order to cause the trajectory of the bullets to pass through the horizontal plane of the gun at a selected distance ahead of the ship (for example, 300 yards), and the setting 10 would indicate the amount of convergence of the guns in order to cause the bullet trajectories to cross each other or converge at the same distance (300 yards) ahead of the airplane. In such bore sighting, convergence of the bullet trajectories at a greater distance ahead of the ship can be effected by adjusting the cross hairs 23 and 21 to scale marks of proper value on the scales 24 and 25 (e. g. 40 and 15) and convergence at a shorter distance ahead of the ship can be attained by adjusting the cross hairs to scale marks of opposite value (e. g. 60 and 5). It is obvious that right and left hand gun installations will be read oppositely on scale 25.

The target device is successively applied to each pair of fittings 12 after having been adjusted to the proper reading for that gun, and the gun is adjusted by manipulating the mechanism 10 until the bore of the barrel 7 is aligned with the target 20.

In sighting through the barrel, use is made of a sighting device 32 which, by means of a prism, reflects the line of sight at a 90 degree angle. This sighting device is simply inserted into the breach end of the barrel 7 as indicated in Fig. 3 and the sighting is done from above.

It is to be understood that the invention is equally applicable to the bore sighting of guns that are mounted in other structures and in parts of the structure of an airplane other than the leading edges of the wings.

I claim as my invention:

1. Apparatus for bore sighting the barrel of a

gun adjustably mounted in a fixed part of an airplane comprising a target frame having a central opening and a plurality of pilot pins adapted to be received in pilot openings located in said fixed airplane part in accordance with the previous positioning of said gun by an original target sighting process, said frame also having a dial face provided with vertical and horizontal scale marks, and a transparent target window adjustably secured to said dial face and having thereon a target to be lined up with the bore of said gun through said opening and also having thereon scale marks adapted to be related to the scale marks on said dial face in order to determine a desired position of adjustment of said target with reference to said dial face.

2. Apparatus for bore sighting the barrel of a gun adjustably mounted in a fixed part of an airplane, comprising a target frame having a central opening and having pilot means cooperable with pilot means on said fixed airplane part for orienting said frame in a predetermined position with reference to said part with said opening generally aligned with the barrel of said gun, said frame also having a dial face provided with scale marks; and a transparent target window adjustably mounted on said dial face and having thereon a target adapted to be sighted through the barrel of said gun and a plurality of scale marks adapted to be related to the scale marks on said dial face to determine a desired position of said target with reference to said dial face and thereby determine a desired positioning of said gun; said target window and frame each having a pair of parallel slots, the slots of one being vertical and the slots of the other being horizontal, and including clamping bolts extending through respective slots and adapted to clamp said target window to said dial face in a desired position of adjustment.
